(57) **CLAIM**

The ornamental design for a wheel with maltese cross, as shown and described.

DESCRIPTION

FIG. 1 is a perspective view of a wheel with maltese cross of the present invention showing my new design; and, FIG. 2 is a front elevational view of the wheel with maltese cross of FIG. 1, the rear elevational view being a mirror image thereof.

The broken lines in the Figures are intended to show environment, but form no part of the claimed design.
